UNITED STATES PATENT OFFICE.

JOSEPH O. ANDERSON, OF BERCAIL, MONTANA.

MAIL RECEIVER AND DELIVERER.

No. 920,239.

Specification of Letters Patent.

Patented May 4, 1909.

Application filed July 8, 1908. Serial No. 442,622.

To all whom it may concern:

Be it known that I, JOSEPH O. ANDERSON, a citizen of Sweden, residing at Bercail, in the county of Fergus and State of Montana, 5 United States of America, have invented certain new and useful Improvements in Mail Receivers and Deliverers, of which the following is a specification.

The present invention appertains to mechanical appliances for receiving and delivering mail from moving trains and has for its object to provide a structure effective for the purpose intended and positive and certain in operation, the means being reversible and 10 movable to admit of shifting from one side of the car to the other or to be turned according to the direction of travel of the car.

For a full understanding of the invention and the merits thereof and also to acquire a 20 knowledge of the details of construction and the means for effecting the result, reference is to be had to the following description and accompanying drawings.

While the invention may be adapted to 25 different forms and conditions by changes in the structure and minor details without departing from the spirit or essential features thereof, still the preferred embodiment is shown in the accompanying drawings, in 30 which:

Figure 1 is a perspective view of means for receiving and delivering mail embodying the invention. Fig. 2 is a horizontal section on the line 2—2 of Fig. 1. Fig. 3 is a top plan 35 view of the base provided with the catcher and engaging means fitted to the lower arm of the swinging frame. Fig. 4 is a section on the line 4—4 of Fig. 3.

Corresponding and like parts are referred 40 to in the following description and indicated in all the views of the drawings by the same reference characters.

At one side of the track is placed a post 1 which is provided with arms 2, 3 and 4 supporting the means for receiving and holding 45 the mail in proper position. The arm 2 receives the catcher and the arms 3 and 4 are provided with the means for holding the mail bag when placed to be delivered to the moving train. A base 5 is pivoted upon the arm 2 and is adapted to be turned about the pivot fastening as an axis. The ends of the 50 base 5 are made rounding so as to obtain a

close fit with the part of the arm 2 abutting against the end of said base. A pin 6 is 55 adapted to hold the base 5 in the adjusted position, that is, with the catcher facing either up or down track. The upper portion of the arm 2 is recessed to receive the base 5, the shoulder formed at the inner end of the 60 recess being rounding to conform to the rounded ends of the base 5. Catcher arms 7 are pivoted at their inner ends to the base 5 and their outer ends flare to properly direct the back or other container into the space 65 formed between the said arms. A keeper 8 consisting of an arch, has its vertical members secured to the base 5 and embraces the upper and outer sides of the catcher arms and limits their opening movement. Pins 9 70 project from the base 5 and are adapted to engage with the inner sides of the catcher arms and limit their opening movement. Pins 9 project from the base 5 and are adapted 75 to engage with the inner sides of the catcher arms and limit their closing movement. A spring 10 of the contractile type normally exerts a pressure to draw the catcher arms together so as to hold the bag or container and prevent displacement thereof. The opposite portions of the catcher arms are outwardly curved, thereby forming a space between said arms when closed to hold and retain the mail bag or like container receiving the mail or other matter to 80 be delivered. Inner projections 11 constitute abutments to engage with and limit the inward movement of the mail bag when received between the catcher arms. A spreader bar 12 holds the catcher arms 7 separated 85 at their outer ends when set to receive the mail. This spreader bar is pivoted at one end to one of the catcher arms and is connected to the other catcher arm by means of a pin 13, the latter operating in an L-slot 14 95 formed in the end portion of the spreader bar remote from its pivot end. The pin 13 is headed and the shoulder formed by the lateral extension at the outer end of the slot 14 engages with the pin 13 and holds the 100 outer ends of the catcher arms separated or spread. The spreader bar 12 is arranged a short distance in front of the inner projections or abutments 11 so as to be engaged by the bag or container when received between 105 the catcher arms, thereby releasing the

spreader bar so that the catcher arms may be permitted to close upon the bag received between them and hold it in place.

A base 15 is pivoted upon the arm 3 to swing horizontally about its pivot connection as a vertical axis. A latch bolt 16 mounted upon the arm 3 engages with the base 15 and holds the same in either of its two extreme positions. The base 15 is provided with engaging means for sustaining the mail bag or container in position to be delivered to the catcher of the moving train. The engaging means consist of arms 17 arranged in parallel position and pivoted between their ends to the base 15. A spring 18 of the contractile type connects the outer members of the arms 17 and holds them closed so as to retain the ring, loop or like part of the bag or container placed in position between them. A stop 19 is fitted to the base 15 and arranged between the arms 17 and holds them in a given position. This stop 19 consists of a rod or stout wire arched between its ends to span the spring 18 and having its extremities let into or secured to said base in any manner. The bar or projecting ends of the arms 17 are tapered and oppositely curved to receive the suspending device, such as the ring or loop of the mail bag. The arm 4 is provided with engaging means for holding the mail bag in place. The engaging means illustrated consist of hooks 20 pivoted at their lower ends to the extremity of the arm 4. A contracting spring 21 connects the hooks 20 and normally exerts a pressure to draw the latter together. Pins 22 projected from the arm 4 extend between the hooks 20 and form stops to limit their inward or closing movement. The lower ring or loop of the mail bag 23 is received between the hooks 20, whereas the upper ring or loop is held between the arms 17, the mail bag being thus held in position for delivery to the catcher of the train. A guard 24 is applied to the post 1 at a point between the arms 2 and 3 and by preference is located near the arm 3. This guard prevents interference of the bag or container delivered to the catcher of the post with the bag or container suspended between the arms 3 and 4. The guard consists of a rod or bar having a crank portion 25 at one end and which crank portion is pivotally connected to the post to admit of the guard being turned from one side of the post to the other, according to the direction of travel of the car. It is to be understood that the guard is arranged to project from the same side of the post as the catcher to engage with the mail delivered thereto and prevent the same interfering with the mail suspended between the arms 3 and 4 to be delivered to the train.

A swinging frame is applied to a side of the car at one side of the door opening so as to be

swung outward to bring the catcher in position to receive the mail from the station and the mail bag container carried by the train in position to be delivered at the station. This frame comprises an upper arm 26, a lower arm 27 and an upright 28 connecting the inner ends of the arms 26 and 27. When the frame is swung outward, it is held in position by means of a catch 29 and a brace 30, the latter being pivoted at one end to the arm 27 and having its opposite end formed with a head 31 to enter a socket 32, attached to a side of the car a short distance from the door opening. A head 31 interlocks with the socket 32, thereby fixing the position of the swinging frame and preventing any rebound thereof due to shock when receiving and delivering mail. The arm 27 is adapted to receive and support a base 33 which is reversible, the same being provided with keepers 34 which receive the outer portion of the arm 27, said base 33 being placed in position or removed from the arm 27 by means of an endwise sliding movement. The base 33 is provided with a catcher substantially the same as the catcher applied to the base 5, hence a detail description thereof is not deemed necessary, since corresponding parts are indicated by like reference numerals and the previous description serving to give a clear understanding thereof. Each end of the base 33 is provided with engaging means, the same being a duplicate of the engaging means applied to the outer end of the arm 4. The engaging means consist of hooks 20 and junctive parts substantially as herein disclosed and designated by like reference numerals indicating corresponding parts of the engaging means at the outer end of the arm 4.

Engaging means receiving the ring, loop or like part at the upper end of the mail bag, are fitted to the outer end of the arm 26 and are substantially the same as the engaging means applied to the arm 3. The base 33 is pivoted to the arm 26 and is held in either of its two positions by means of a latch bolt 16, and arms 17 are mounted upon the base 33 in a manner similar to the arms mounted upon the base 15. Pins 36 limit the closing of the arms 17, the latter being drawn together by means of a spring 18, as indicated herein.

The bag or other container supplied with the mail or other matter to be delivered from the station to the train is suspended between the arms 3 and 4 of the post 1 by the engaging means applied to said arms. The bag or like container holding the mail or other matter to be delivered from the moving car is suspended between the arms 26 and 27 of the swinging frame by the engaging means applied to said arms. As the train approaches the station, the mail bag carried by the swinging frame is delivered to the catcher of the post 1 and the mail bag suspended between the

arms 3 and 4 of the post 1 is turned up by the catcher applied to the arm 27 of said swinging frame.

The operation will be readily understood 5 from the foregoing in connection with the accompanying drawings, hence a detailed description is not deemed necessary.

Having thus described the invention, what is claimed as new is:

10 1. In means for receiving and delivering mail, the combination of a supporting arm, a base mounted upon said arm and adapted to be turned end for end, means for securing said base to the arm in the required position, 15 and engaging means carried by said base.

2. In means for receiving and delivering mail, the combination of a support, catcher arms pivoted to said support, means for normally exerting a force to close said catcher 20 arms, and a spreader bar for holding said catcher arms separated at their receiving ends and adapted to be released by impact of the mail therewith, said spreader bar having connection with one of the bars to move 25 therewith and having sliding connection with the other arm.

3. In means for receiving and delivering mail, the combination of a support, a series 30 of three arms projected from the support, one of said arms being provided with a catcher, and the other two arms having engaging means for suspending a mail bag in position for delivery, and a reversible guard attached to the aforesaid support at a point 35 between the upper arm provided with the catcher, and the arm next below having one of the said engaging means.

4. In means of the character described, the combination of a support, oppositely disposed pivoted catcher arms having their 40 outer ends flared and their opposing sides adjacent to the flared ends made hollow to form the receiving space for the mail container, a spring normally exerting a force to

close the catcher arms and located in the rear 45 of said receiving space, and a spreader bar arranged between the receiving space and the spring for holding the outer ends of the catcher arms separated and having pivotal connection with one of the said arms and 50 sliding connection with the other arm and adapted to be released by impact of the mail therewith to permit automatic closing of the catcher arms upon the mail received between them.

5. In means of the character described, the combination of a support, oppositely disposed pivoted catcher arms having their outer ends flared and their opposing sides made hollow to form a space to receive the 60 mail container, means normally exerting a force to close the catcher arms, and a spreader bar for holding the outer ends of the catcher arms separated and adapted to be released by impact of the mail therewith and 65 permit automatic closing of the catcher arms upon the mail received between them, said spreader bar being pivoted at one end to one of the catcher arms and having its opposite end portion provided with an L-slot, and a 70 pin applied to the other catcher arm and arranged to operate in said L-slot.

6. In means of the character specified, the combination of upper and lower arms, bases mounted upon said arms each adapted to be 75 turned end for end, engaging means fitted to the upper base, a catcher fitted to the lower base, and engaging means at opposite ends of said lower base to admit of one being in operative position according to the adjustment 80 of the lower base to the direction of travel of the car.

In testimony whereof I affix my signature in presence of two witnesses.
